DIAL HAND FOR RADIO RECEIVERS AND
THE LIKELester R. Snow, Winchester, Mass., assignor to
J. H. Winn's Sons, Winchester, Mass., a firm

Application June 25, 1940, Serial No. 342,258

8 Claims. (Cl. 116—124.2)

This invention relates to dial hands particularly adapted for use in radio receivers and the like and has for its main object the construction of an ornamental hand at minimum expense.

One object is the provision of a button formed of translucent plastic material and adapted to be secured fixedly in an opening in the body portion of a metal hand.

Another object is the provision of ornamental designs on the front face of said button.

A further object is the provision of a tubular shaft-receiving hub formed integral with said button.

These objects are attained by the mechanism illustrated in the accompanying drawing.

For the purpose of illustrating the invention, one preferred form thereof is illustrated in the drawing, this form having been found to give satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claims.

Of the drawings

Figure 1 represents a front elevation of dial hand for radio receivers embodying the features of the present invention.

Figure 2 represents a horizontal section of the same on line 2, 2 on Fig. 1.

Figure 3 represents a vertical section of the same on line 3, 3 on Fig. 1.

Figure 4 represents a rear elevation of the central plastic element or button of said dial hand.

Figure 5 represents a front elevation of a modified form of said dial hand.

Figure 6 represents a vertical section of the same on line 6, 6 on Fig. 5.

Figure 7 represents a front elevation of another modified form of said dial hand, and

Figure 8 represents a vertical section of the same on line 8, 8 on Fig. 7.

Similar characters indicate like parts throughout the several figures of the drawing.

In the drawing, 10 is the body portion of a dial hand for radio receivers having an ornamental extension 11 radiating therefrom, and from the outer end of this extension 11 projects a pointer 12.

The body portion 10, extension 11 and pointer 12, are preferably formed integral of thin stamped metal.

The body portion 12 has a central opening 13 therein which may be of any desired shape being shown in Figs. 1, 2, 3, 5 and 6 as round, and in Figs. 7 and 8 as square.

Disposed in the opening 13 is a button 14 of moulded translucent plastic material, such for instance, as "Plastacele." "Plastacele" is the trade name of a Du Pont product No. C6505, and is a ruby red fluorescent cellulose acetate which has been found to be particularly well adapted for use in manufacturing the button 14.

The outer end of this button 14 is convex and preferably has projecting outwardly therefrom one or more ribs 15 formed integral therewith.

In Figs. 1, 2 and 3, two ribs 15 are shown in parallelism, in Figs. 5 and 6 a plurality of concentric ribs 15 are shown, and in Figs. 7 and 8 a single zigzag rib 15 is shown.

The inner end of the button 14 has a tubular hub 16, the wall of which is provided with a plurality of slots 17 extending from its outer end, three of these slots being preferable.

The bore 16x of the hub 16 is adapted to tightly fit the reduced end 18 of a spindle or shaft 19 forming a part of the radio on which the hand is to be used.

The bore 16x is very slightly tapered so that when the button 14 is forced onto the end 18 of spindle 19 it will firmly grip thereon.

The portions of the tubular extension 16 between the slots 17 are provided with reinforcing ribs 20 extending endwise of said hub 16.

The inner end of the body portion of button 14 is provided with an annular flange 21 which bears against the rear inclined wall of the body portion 10 of the dial hand.

The periphery 22 of the outer end of the member 14 is slightly tapered so that when the member 14 is forced through the opening 13 of the body portion 10 of the dial hand, said hand will be firmly locked thereto, thus insuring the rotation of the hand with the button 14.

The opening 13 has a diameter about .002" smaller than the diameter of the tapered outer end 22 of the button 14, and when the outer end of the button 14 is pushed through the opening 13, the wall of the opening 13 will sink into the plastic material and prevent any displacement of the button.

Heretofore, dial hands for radio receivers have had the hub 16 formed as a separate element which must be soldered to the body portion 10 of the dial hand.

This soldering is expensive and not always effective. It is a slow operation and by dispensing

with this operation and using the plastic button 14, the manufacture of the dial hands is greatly speeded up.

By the use of the plastic buttons 14 a more effective dial hand is produced at much less cost.

While ribs 15 are shown on the outer end of the button 14, it is obvious that any desired design may be moulded into the outer face.

These plastic buttons 14 may be of any desired color or finish while the outer face of the metal part of the hand may have a contrasting color which makes the entire completed hand very attractive.

The button 14 being translucent the rays of light from the radio lamps will be transmitted 15 therethrough, causing a bright glow on the outer end of the button, thus increasing the decorative effect of the hand when in use.

When the button 14 is illuminated in this manner, it will serve to indicate that the radio is in 20 operation.

The front of the button 14 may be polished to make a nice finish.

It will be noted that the use of the button 14 formed of moulded plastic material has several 25 distinct advantages.

For instance, it eliminates soldering, makes it possible to speed up production, reduces the cost of manufacture, makes it possible to combine metal and plastic materials in harmonizing and 30 contrasting colors, and provides a means whereby a colored light may be shown on the face of the button, thereby giving a novel and useful effect.

The slots 17 in the hub or bushing 16 are about 35 .031" wide and moulded in the button 14.

These slots 17 serve to permit the expansion of the hub or bushing 16 to obtain a tight fit when an oversize shaft 18 is used.

The shaft 18 is .125" in diameter at its inner 40 end and about .001" less in diameter at its outer end to form a slight taper, and the inner diameter of the hub or bushing is slightly smaller as .123" so as to get a good grip on the shaft 18 when the latter is inserted into the bore of said 45 hub or bushing 16.

In some cases the bore 16x may be moulded larger than .123" according to the diameter of the shaft to which the button is to be applied. For some shafts it is necessary to have a .250" 50 bore.

It is believed that the many advantages of a radio dial hand constructed as herein shown and described will be readily understood without further description.

Having thus described my invention, I claim:

1. A dial hand for radio receivers comprising a stamped metal body portion having a pointer radiating therefrom, said body portion having an opening therethrough, and a button of translucent plastic material fixedly secured in said opening and including means for attachment thereof to a rotatable shaft of a radio receiver.

2. A dial hand for radio receivers as set forth in claim 1, in which said button is translucent and is provided on its front face with means for refracting rays of light.

3. A dial hand for radio receivers as set forth in claim 1, in which the front face of said button is provided with outwardly extending concentric ribs constructed and arranged with side faces for refracting rays of light.

4. A dial hand for radio receivers as set forth in claim 1, in which said button is provided with a rearwardly extending tubular hub to receive the end of a rotatable shaft of a radio receiver.

5. A dial hand for radio receivers as set forth in claim 1, in which said button is provided with an elongated rearwardly extending tubular hub having at its outer end spaced expansion slots in the peripheral wall thereof.

6. A dial hand for radio receivers as set forth in claim 1, in which the rear end of said button is provided with an annular flange constructed and arranged to bear against the rear face of said metal body portion.

7. A dial hand for radio receivers as set forth in claim 1, in which the central portion of said button extending through the opening of said body portion is tapered to tightly fit the inner wall of said opening and prevent movement thereof relatively to said body portion.

8. A dial hand for radio receivers as set forth in claim 1, in which said button is provided with an elongated rearwardly extending tubular hub having at its outer end spaced expansion slots in the peripheral wall thereof and reenforcing ribs on the periphery of said hub extending lengthwise thereof between said slots.

LESTER R. SNOW.
